DIPHENYL-SUBSTITUTED SEMICARBAZIDES

Samuel M. Darling, Lyndhurst, Ohio, assignor to The Standard Oil Company, Cleveland, Ohio, a corporation of Ohio

No Drawing. Original application September 23, 1953, Serial No. 381,975. Divided and this application August 19, 1954, Serial No. 451,033

4 Claims. (Cl. 260—554)

The present invention relates to color stabilizing additives for mineral lubricating oils, which additives are useful in improving the stability of the oil against color development on storage.

In the refining of mineral lubricating oils, it is a goal of the industry to produce oils having as light a color as possible and, for this reason, several additional processing steps are often incorporated in the refining operation. Although the petroleum industry has been able to produce light colored oils, it is a known fact that the oils nevertheless tend to darken upon prolonged storage. The darkening of an oil in storage is very undesirable since consumers greatly prefer light colored oils and, as a consequence, the salability of oils which have darkened in storage is adversely affected. In order to overcome the tendency of an oil to develop color on storage, the art has for a long time sought means for improving the color stability of lubricating oils.

It is an object of the invention to provide new chemical compounds which are useful as additives for preventing color development in a mineral lubricating oil.

The present invention is based in part on the discovery that certain derivatives of 4,4-diphenyl semicarbazide are effective color stabilizers for mineral lubricating oil. The additives contemplated in the present invention have the general formula:

wherein R is an alkyl radical containing at least 4 and preferably not more than about 20 carbon atoms or an aralkyl radical having at least 7 and preferably not more than about 22 carbon atoms.

It has been found that lubricating oils containing the additives of the invention are remarkably stable against color development on storage even in the presence of a metal catalyst. The concentration of the additive in the composition should preferably be not less than 0.001% by weight up to the upper limit of solubility, generally not over 2% by weight, with the optimum results being achieved at a concentration of about from 0.6 to 1% by weight of the additive based on the weight of the mineral lubricating oil.

The mineral oils in which the additives are incorporated may be any oil of lubricating viscosity. Several different oils have been tried ranging from motor oils to

2

light machine oils and excellent results have been obtained with all of these oils.

In the general formula typical radicals which R may represent are butyl, including isobutyl, secondary butyl and tertiary butyl; amyl, including the branched chain amyl radicals, hexyl, heptyl, nonyl, decyl, dodecyl, etc. Also such radicals as phenylmethyl, phenylbutyl, phenylamyl, phenylnonyl, phenyldecyl, phenyldodecyl, and other similar radicals, in which the alkyl groups may be either straight or branched chain, are satisfactory.

The additives can be prepared starting from 4,4-diphenyl semicarbazide by reacting the starting compound with an aldehyde to produce an aldehyde semicarbazone. The aldehyde semicarbazone is then reacted with the appropriate Grignard reagent to produce the particular semicarbazide derivative that is desired.

The addition of the additive to the mineral lubricating oil can be effected by dissolving the desired amount of additive in the lubricating oil and the solution of the additive can be accelerated by warming the mineral oil slightly.

The following preparations illustrate the preparation of several additives which can be used in the present invention.

25

PREPARATION A

1-(1-PHENYLNONYL)4,4-DIPHENYL SEMICARBAZIDE

Into a reaction vessel there was placed 55.6 g. (0.2446 mol) of 4,4-diphenyl semicarbazide and 24.6 g. (0.2446 mol) of hydrochloric acid in alcohol solution. The resulting mixture was stirred and then allowed to stand until the hydrochloride salt had time to form and precipitate. There was obtained by filtration 20 g. of a wet precipitate. The wet precipitate and 40 g. of sodium acetate (0.5 mol) as a buffer were then added to a solution of 25.68 g. (0.2446 mol) of benzaldehyde in 200 ml. of alcohol. The mixture was stirred vigorously and then placed in a beaker of boiling water and after the boiling water had cooled, the mixture was then placed into a beaker of ice. When precipitation was complete, the resultant benzaldehyde semicarbazone was filtered, washed with water, and dried overnight in a vacuum drying tube. The yield was 63.15 g. which is about 81.37% of the theoretical yield.

The 63.15 g. of benzaldehyde semicarbazone was then placed in a second vessel under an atmosphere of nitrogen and 300 ml. of anhydrous ethyl ether was added. Thereafter, 103.8 g. of octyl magnesium bromide was added dropwise with constant stirring and after standing for one hour, 300 ml. of distilled water was added dropwise with stirring in order to hydrolyze the excess octyl magnesium bromide. After an excess of water had been added, the mixture separated into two phases and the water layer was extracted with additional ether. The ether layer resulting from this extraction was then evaporated to dryness to obtain a higher boiling liquid layer comprising the final product. The oily product was identified as 1-(1-phenylnonyl)4,4-diphenyl semicarbazide. The refractive index of the product was 1.5459.

PREPARATION B

1-(1-PHENYLHEXYL)4,4-DIPHENYL SEMICARBAZIDE

A slurry consisting of 64.5 g. of benzaldehyde 4,4-diphenyl semicarbazone and 200 ml. of anhydrous ethyl ether was formed in a reaction vessel equipped with a stirrer, reflux condenser and a dropping funnel. After

filling the flask with nitrogen, there was added 100.3 g. of amyl magnesium bromide dropwise over a period of about four hours. The reaction mixture was then allowed to stand overnight and there was then added 200 ml. of distilled water to hydrolyze the excess of amyl magnesium bromide. After an excess of water had been added the mixture separated into two layers and the ether layer was evaporated to obtain a higher boiling liquid layer comprising the final product which was identified as 1-(1-phenylhexyl)4,4-diphenyl semicarbazide. This oily liquid had a refractive index of 1.5631. The yield was 81.5% of the theoretical.

Chemical analysis of the product was as follows:

Weight Percent	Found	Theory
C.....	76.97, 77.11	77.4
H.....	7.80, 7.91	7.53
N.....	10.05, 10.05	10.89

PREPARATION C

1-SECONDARY BUTYL-4,4-DIPHENYL SEMICARBAZIDE

There was placed in a reaction vessel a solution of 15 g. (0.066 mol) of diphenyl semicarbazide in alcohol. 6.6 g. of 37% hydrochloric acid (0.066 mol) was then added and the mixture was stirred vigorously until the hydrochloride salt had precipitated. The precipitate was recovered by filtration. In a separate reaction vessel there was placed a solution of propionaldehyde dissolved in 240 ml. of ethyl alcohol. Twenty-four grams (24 g.) of the wet precipitate and 36 g. of sodium acetate buffer

product was identified as 1-secondary butyl-4,4-diphenyl semicarbazide. It was an oily liquid having a refractive index of 1.5506.

The following examples are presented in order to illustrate the invention and its attendant advantages:

Examples 1 through 7

A number of compositions within the scope of the invention were prepared by dissolving different additives in varying amounts in several different samples of mineral lubricating oil. The samples were then subjected to an accelerated storage test. In this test a 50 ml. sample of oil was placed in an open 100 ml. container and the container was placed in a circulating hot air oven at a temperature of 210° F. and allowed to remain there for 120 hours. By measuring the optical density of the oil before and after the test with a Coleman spectrophotometer, the color stability of the oil was determined. The oils used in these examples were either a straight paraffin distillate or a fraction of the straight paraffin distillate. The paraffin distillate used in the examples is a wide boiling range oil having a viscosity of about 95 S. S. U. at 100° F. The remaining oils are narrow fractions of the paraffin distillate having viscosities as follows:

Torch.....	50 S. S. U. at 100° F.
Straw.....	80 S. S. U. at 100° F.
Diamond.....	110 S. S. U. at 100° F.
Zone.....	160 S. S. U. at 100° F.

The results of these examples are summarized in the following table:

TABLE I

Example No.	Additive	Concentration		Oil	Optical Density		
		Wt. Percent	Mol. Percent		Initial*	Final With Additive	Without Additive
1.....	1-(1-phenylhexyl)4,4-diphenyl semicarbazide.	1.05	0.8	Paraffin Distillate.	2.0	18.2	28.2
2.....	1-(1-phenylhexyl)4,4-diphenyl semicarbazide.	2.10	1.6	Paraffin Distillate.	2.0	37.1	28.2
3.....	1-(1-phenylhexyl)4,4-diphenyl semicarbazide.	0.92	0.8	Paraffin Distillate.	5.5	13.7	49.8
4.....	1-(1-phenylhexyl)4,4-diphenyl semicarbazide.	1.84	1.6	Paraffin Distillate.	5.5	20.0	49.8
5.....	1-(1-phenylhexyl)4,4-diphenyl semicarbazide.	0.01	0.009	Torch Paraffin.	2.2	8.5	23.1
6.....	1-secondary butyl-4,4-diphenyl semicarbazide.	0.64	0.8	Paraffin Distillate.	5.5	17.3	49.8
7.....	1-secondary butyl-4,4-diphenyl semicarbazide.	1.28	1.6	Paraffin Distillate.	5.5	29.8	49.8

*Initial Optical Density Measurements Made on Sample Without Additive.

were added. The mixture was then shaken vigorously and was placed in a container of boiling water and allowed to remain there until the water had cooled. The mixture was then cooled in ice until crystallization was complete and the crystalline product was filtered and dried in a vacuum drying apparatus overnight. There was obtained 8.9 g. of propionaldehyde 4,4-diphenyl semicarbazone which represented 50.2% of the theoretical yield.

The propionaldehyde 4,4-diphenyl semicarbazone then placed in a separate reaction vessel and slurried in dry ether under nitrogen atmosphere. One hundred thirty milliliters (130 ml.) of methyl magnesium bromide was then added dropwise from a dropping funnel and when the reaction was complete, the mixture was hydrolyzed with water to form the semicarbazide. This resulted in the formation of two layers, an ether layer and a water layer, which were separated by decantation and the ether layer was evaporated to yield 5.3 g. of product. The

It is evident from the data that the compositions of the invention demonstrate a marked improvement in color stability.

The only example in which no improvement was noted is Example 2 and in this example the concentration of additive exceeded the optimum concentration for the particular oil used therein.

Examples 8 through 20

Another series of compositions was prepared as in Example 1 and the samples were subjected to a catalyzed oven test for the determination of storage stability. In this test, the sample was placed in the oven as in the uncatalyzed test but two metal strips, one of copper and one of steel, each 0.5 x 1.5 inches, were immersed in the oil and the test was run for 72 hours instead of 120 hours.

As in the preceding example, the optical density of the oil was measured before and after the test.

TABLE II

Example No.	Additive	Concentration		Oil	Optical Density

*Initial Optical Density Measurements Made on Sample Without Additive.

Again the data shows the marked improvement in color stability which is possessed by the compositions of this invention. From the examples it is also apparent that the additives are effective over a fairly wide range of concentration.

It is intended to cover all changes and modifications in the examples of this invention herein given for purposes of disclosure which do not constitute departure from the spirit and scope of the appended claims.

This application is a division of my application Serial Number 381,975, filed September 23, 1953.

I claim:

1. Compounds having the formula,

wherein R is selected from the group consisting of alkyl radicals having from 4 to about 20 carbon atoms and aralkyl radicals having from 7 to about 22 carbon atoms.

2. 1-(1-phenylnonyl)4,4-diphenyl semicarbazide.
3. 1-(1-phenylhexyl)4,4-diphenyl semicarbazide.
4. 1-secondary butyl-4,4-diphenyl semicarbazide.

No references cited.
